UNITED STATES PATENT OFFICE.

WILLARD GLENN HENKLE, OF GARRISON, IOWA.

LOCKING DEVICE FOR GATES.

1,253,822.

Specification of Letters Patent. Patented Jan. 15, 1913.

Application filed July 16, 1917. Serial No. 130,821.

To all whom it may concern:

Be it known that I, WILLARD GLENN HENKLE a citizen of the United States of America, and a resident of Garrison, Benton county, Iowa, have invented certain new and useful Improvements in Locking Devices for Gates, of which the following is a specification.

My invention relates to improvements in locking devices for gates, and the object of my improvement is to furnish an easily operated, secure and inexpensive means for releasably securing a gate in closed position.

This object I have accomplished by the means which are hereinafter described and claimed, and which are illustrated in the accompanying drawings, in which Figure 1 is an elevation of a gate and gate-posts having my improved locking-device mounted on one of the posts; Fig. 2 is an enlarged elevation of the locking-device; Fig. 3 is a side view thereof; Fig. 4 is a top plan thereof, with both of the gravity retaining means in locked positions, and Fig. 5 is a like view, showing one of the gravity-retaining means released with the bifurcated locking-plate swung to an open position.

Similar numerals of reference denote corresponding parts throughout the several views.

In Fig. 1, I have shown a gate of the adjustable flexible type, having tubular front and rear stiles 19 and 20, connected by top and bottom longitudinal tubular beams 21 and 22, the latter having forked couplings mounted on their ends and pivotally connected to the tops and bottoms of said stiles, respectively. A clip 24 is slidably mounted upon the lower part of the front stile, and connected by means of side rods 23 to the upper part of the rear stile, to hold the front stile in a vertically adjusted position. The front and rear stiles may be connected also by means of meshed wires 25 and 26. The rear stile is supported on hinges 27 mounted on a rear post 28, while my improved gate fastening means is mounted on the front post 29.

Referring now to Figs. 2 to 5, inclusive, the numerals 1 and 14 denote like base-plates bolted to the upper and lower parts of the front post 29 opposite the front stile 19 and spaced therefrom. Each base-plate has like vertically-spaced parallel flat plates 2 and 3, and 15 and 16, while like locking-plates 5 and 17, having diverging forks 6, are pivoted be-

tween them on pivot-bolts 8 and 18 respectively, and secured by nuts, 9. The outer parts of the upper and lower faces of said forks 6 may be narrowed in thickness at 7 60 to give clearance to the upper parts 12 of the gravity-retaining rods 10, when locking-plates are swung laterally, as shown in Fig. 5. Upon the tops of the upper plates 2 and 14 are like pairs of integral bosses 4, and these bosses also both plates 2 and 3 thereunder, are provided with orifices in vertical alinement to slidably and rotatably receive the depending ends 13 from the horizontal parts 12 of offset parts 11 of the rods 10, the 70 lower ends of said rods being both slidably and rotatably mounted in like bearing orifices in the lower lugs 15 and 16 of the lower base-plate 14. The forks 6 and 17 respectively, of said upper and lower locking-75 plates inclose the front stile 19 of the gate when in a closed position, as shown in Fig. 4. In this closed position, the squared end of the locking-plate 5 abuts upon the depending parts 13 of the rods, that is, these 80 depending parts 13 in passing through the said bearing orifices in both plates 2 and 3, contact and lock the squared end of said locking-plate to hold it fixed while the forks 6 are inclosing the front stile 19, to hold the 85 gate fastened to the front post 29.

To open the gate, as will be seen by referring to said Fig. 5, it is merely necessary to manually lift one of the rods 10 by means of the offset parts 11-12, which disengages the 90 depending part 13 from the lower lug 3 and from the squared end of the locking plate 5, as indicated by the dotted lines in said Fig. 2, so that the locking-plate may be swung to the same side, simultaneously swinging the 95 gate, and releasing its stile 19 from the forks 6.

When the gate is swung back to close it, the stile 19 engages the further one of the forks 6 of said locking plate, and swings 100 it to its first position shown in Fig. 4, thus again inclosing the stile and releasing the part 13 of said rod which had previously been riding upon said latch, so that by the action of gravity, it will drop back into the 105 orifice in the lower plate 3, the lower end of the rod also dropping into the orifice in the lower plate 16, whereby the upper and lower locking plates 5 and 17 are securely locked about said stile, by the reengagement 110 of the rod-part 13 with their squared ends.

It will be seen that by this means, both

the upper and lower ends of the stile 19 are simultaneously released or locked by one simple operation, and that there is no catch or projection upon the stile to engage passing vehicles.

Since the base-plates with their parts, the locking-plates and the gravity retaining means, are duplicates of each other in form and dimensions, this locking-means may be 10 manufactured economically, the parts are interchangeable, and the dealer has to keep only a minimum number of parts in stock, while repairs are therefore more easily made.

15 As shown by the dotted lines in Fig. 2, when either rod 10 is in its lifted or released position, its cross-part connecting to the offset part 11 engages the bottom of the lower plate 3, thus preventing further upward movement so that the parts of the rod cannot be disengaged from its bearings.

Having described my invention, what I claim as new, and desire to secure by Letters Patent, is:

25 1. A locking device for gates, including separated pairs of spaced orificed parallel plates, means for mounting said plates upon a gate post, a bifurcated locking-plate pivotally mounted between each pair of 30 spaced plates and each adapted to receive the adjacent end stile of a gate, and gravity movable retaining means removably mounted upon said pairs of spaced plates, and normally coacting with both said locking plates to hold both of them against pivotal 35 movements, said means consisting of a pair

of like rods having parts mounted slidably to rock in the orifices in said pairs of spaced plates engaging said locking-plates to hold them in locked positions, each rod having an offset part adapting it for manual actuation to lift it disengaging it from certain of said spaced plates and from said locking-plates to release the latter.

2. A locking device for gates, including separated pairs of spaced orificed parallel plates, means for mounting said plates upon a gate-post, a bifurcated locking-plate pivotally mounted between each pair of spaced plates and each adapted to receive the adjacent end stile of a gate, and gravity movable retaining means removably mounted upon said pairs of spaced plates, and normally coacting with both said locking-plates to hold them against pivotal movements, said means consisting of a pair of like rods each having its upper part bent horizontally, then vertically, then returning horizontally and having a depending part mounted slidably to rock in the orifices in the upper spaced plates to engage the locking-plate pivoted thereon, the lower horizontally bent part of the rod adapted to engage the bottom of the lower one of said spaced plates to prevent the escape of the said depending part from the upper one of the spaced plates when lifted to release said locking-plate.

Signed at Waterloo, Iowa, this 28th day of June, 1917.

WILLARD GLENN HENKLE.
